UNITED STATES PATENT OFFICE

2,415,204

MATCH-BOOK MAKING MACHINE

Nelson E. Garrison, Baltimore, Md., assignor to
Joseph Shapiro, Baltimore, Md.

Application January 10, 1945, Serial No. 572,235

7 Claims. (Cl. 93—2)

1

Match book making machines of the kind to which my invention is directed, each comprises, generally, a magazine for the covers (which magazine includes a gate that carries a first fold form and a slide for feeding the covers, one at a time beneath the gate and first fold form and for pushing the first-folded cover off the first fold form onto a plate where it receives a section of a match comb), a mechanism for feeding the match comb to the covers and severing a section at a time from the comb, a means to effect the second (shorter) fold of the cover, means to center the comb section in the cover and staple the cover and comb together, a match-book-assembling mechanism and a means to deliver the stapled books to the assembling mechanism.

My present invention relates to the match-book-assembling mechanism.

Heretofore the match-book-assembling mechanism included a book-receiving, reversing and delivery mechanism, which included a rotatable head having two diametrically opposite relatively stationary book receivers and two diametrically opposite rotatable book receivers, located 90° from the stationary book receivers and mechanism for rotating the head step-by-step and for turning the rotatable book-receivers by virtue of which the match books are brought to the positions where they are discharged onto the stacking table with their wider and narrower ends alternating. The mechanism which turned the rotatable book receivers included a stationary gear which was located outside the rotatable head and was fastened to the support for the plate on which the covers and comb sections were assembled. In order to replace or adjust the stationary gear (for reasons later to appear) it was necessary to remove the rotatable head, its main shaft and shaft bearing assembly and disconnect the main shaft drive connection and also dismantle a large portion of the book-comb assembly devices in order to get at the screws which held the stationary gear. This caused delays of sometimes several hours in that it was necessary to stop the machines, with consequent loss of production. It is therefore an object of my invention so to improve the match-book-assembling mechanism that repairs and adjustments can be made speedily and without disassembling the cover-comb-assembling and transferring mechanism, and often without having to remove any part of the machine.

Another object is to make the entire book-receiving and reversing mechanism as a complete unit that can be bodily removed from the ma-

2

chine for repairs by simply removing two mounting screws and disengaging a connecting rod from the power applying means.

Other objects will in part be obvious and in part be pointed out hereinafter.

To the attainment of the aforesaid objects and ends the invention further resides in the novel details of construction, combination and arrangement of parts, all of which will be first fully described hereinafter and then be specifically pointed out in the appended claims, reference being had to the accompanying drawings in which:

Fig. 1 is a top plan view of so much of a match book making machine as is necessary to an understanding of my invention.

Fig. 2 is an enlarged top plan view of the match-book-receiving and reversing mechanism unit of my invention.

Fig. 3 is a side elevation of the same.

Fig. 4 is a vertical cross section on the line 4—4 of Fig. 3.

Fig. 5 is an end elevation of the unit shown in Figs. 2 and 3.

Fig. 6 is a detail vertical longitudinal section on the line 6—6 of Figs. 3 and 7.

Fig. 7 is a detail vertical cross section on the line 7—7 of Fig. 6.

Fig. 8 is a detail elevation of the notched centering and stop disc showing the hub on which a ratchet ring is mountable.

Fig. 9 is a detail elevation of the ratchet ring.

Fig. 10 is an enlarged elevation of the magazine unit looking at the gate side and showing the gate and its adjusting device.

Fig. 11 is a detail side elevation showing the gate latch device.

Fig. 12 is a detail section on the line 12—12 of Fig. 10.

In the drawings in which like numerals and letters of reference indicate like parts in all the figures, B represents the bed of the machine on which the cover magazine 1 is mounted. The outlet side (right hand in Fig. 1) is provided with a gate 3 which carries the first fold form 2 beneath which the covers C are fed one at a time by manipulation of the slide 17. The gate 3 is pivoted at 4 and has an arm 5 which lies in contact with the combined stop and gate adjusting member 6. The member 6 has a groove 7 with tapered sides to center the arm 5. In the machines heretofore used the arm 5 was held in contact with the stop by the force of gravity due to the weight of the arm 3 and first fold form 2. Experience has shown that the pivot of the arm sometimes became loose and the vibrations of the

machine would tend to prevent maintaining the gate in its exact position of adjustment to let only one cover to pass at a time. In order to overcome this defect I have provided a latch 10 that is pivoted, at 11, to the frame of the magazine and has a bearing in which a latch rod 12 is mounted. The rod 12 has a teat like end which, when the latch is in its operative position (Fig. 1) lies in the recess 15 under pressure of a spring 13, and holds arm 5 firmly against stop 6 but which may be withdrawn from recess 15 and placed in a recess 16 in the frame of the magazine when it is desired to raise the gate 3 for any desired purpose.

The stop 6 has an eccentric stud 8 held in an opening in the frame of the magazine 4, by a nut 9. By loosening the nut 9 and turning the stop 6 the position of the gate 3 can be readily adjusted to proper position after which the nut 9 is again tightened (see Fig. 12).

After the cover C has been given its first fold over the first fold form 2 (by mechanism not shown) it is pushed by the fingers 17 on the slide 17 onto a plate 20 which extends in a direction transverse to the direction of feeding movement of covers C and match combs M. C., along their slide way 18, and at the same time a part of the comb is inserted between the cover folds and is cut off from the remainder of the comb (by mechanism not shown).

The cover and contents are then advanced by the fork 22 between the cover centerers 23 where the comb section centerers 24 come into play. After the second or short fold is made and the covers and comb section are stapled together on the anvil block 25 (by mechanism not shown) the completed match packet is further advanced into the uppermost receiver 46 (or 42 as the case may be) beneath the hold down finger 65. The head 39 is then turned 90° whereupon pushers 27 on rods 26 that are carried by a reciprocating slide 28 (operated in any suitable way, not shown) push the packet off the receiver onto the stacking table 29 where the packets are held by their side edges.

The plate 20 is mounted on a stationary block 19 that has a shaft bearing hole later again referred to. The anvil or clinch block 25 is also secured to the block 19 by a screw 20. It was to this block 19 that the stationary gear of the packet reversing mechanism was secured in the old machines of the prior art above referred to.

All of the aforesaid illustrated mechanisms designated by the numbers 1 to 9 inclusive and 17 to 29 inclusive are well known parts of the old machines and are not per se a part of my invention.

The invention claimed in this application is illustrated in detail in Figs. 2 to 9 inclusive by reference to which it will be seen that the packet receiving, reversing and delivering mechanism constitutes a complete self-contained unit.

Referring now to these figures it will be seen, the unit composes a casting base 30 that is secured to the bed B (Fig. 3) by bolts 31. The casting includes a bearing 32 for the main shaft 50 of the unit and a split clamp portion 33. The latter is bored, as at 34, to receive the sleeve 36 of the fixed gear 36. The sleeve is tightly held in place by means of a clamp screw or bolt 37 that draws the split parts of the clamp portion 33 together to grip the sleeve 36.

The sleeve 36 may have an annular groove 38 in which a portion of the bolt or screw 37 lies to prevent the gear 36 moving along its axis should

the clamp loosen and yet leave the gear free to be turned on its axis should a gear or pinion break within the head 39 or the parts become jammed.

The head 39 is composed of two sections secured firmly together by screws 40, the halves being provided with aligning pins 41. The head has bearing holes 39' for the bearing sleeves 47 of the rotatable match packet receivers and turners 46. A shaft 48 carrying a pinion 49 is fitted with retaining friction in the sleeves 47. The head has slots 52 to effect communication between the side chambers of the head 39. The side chambers 52' are closed by discs 53 held by screws 54.

Secured rigidly to the head 39 at diametrically opposite places, by screws 43, are a pair of stationary match packet receivers 42. The receivers 42 are located 90° from the rotatable receivers 46. Each receiver 42, 46 is provided with a fixed wear plate 44 and a spring loaded wear plate 45 between which the match packets are received.

The shaft 50 has a hole 51 through which the shaft 48 passes so that the head 39 and shaft 50 will turn, about the axis of the shaft 50, together. The side chambers 52' of the head are supplied with grease to lubricate the gearing and sleeve 36'.

A finger lifting disc 55 has its hub 57 secured to the shaft 50 by a set screw 58. The disc 55 has four equally spaced peripheral depressions 56 to receive a roller 63 on a block 60 which carries a finger 65 that lies over the match packet receiver 46 or 42 that is uppermost. The block 60 is pivoted on a bolt 61 held in an ear 59 by a screw and washer 62 (Figs. 2 and 3). The roller 63 is held yieldably in contact with the disc 55 by means of a spring 64.

A notched centering and back check disc 66 has a hub 67 that is provided with a pin hole 69 in which and through a hole (not seen) in shaft 50 a pin 70 is held to cause disc 66 to turn with shaft 50. The disc 66 has aligning pins 68 which enter aligning holes 75 in a ratchet ring 73 that has a bore 74 to fit on the hub 67. Screws 89 pass through holes 76 into tapped holes 77 to secure the ring 73 to the disc 66. The ratchet ring 73 has four ratchet teeth 73' set 90° apart as best shown in Fig. 9 and disc 66 has four notches 66' set 90° apart. A spring pressed stop pawl 71 is pivoted at 72 and engages the disc 66 as best shown in Figs. 4 and 5.

A rocking pawl carrier 78 is pivoted on shaft 50 and carries a pawl 79 having a stub shaft 80 pivoted to a bearing 82 on the carrier and held in engagement with the ratchet ring 73 by a spring 81. The rocking pawl carrier is retained on the shaft 50 by being held in place by a collar 84 pinned at 85 to the shaft.

The pawl carrier is rocked by means of a rod 86 that is reciprocated by any suitable means such as a cam (not shown), the rod having a stub shaft 87 in a bearing 88 of the rocking pawl carrier 81.

In the operation of the machine the shaft 50 is turned, by the pawl and ratchet mechanisms 86, 79, 73, 78 etc. in successive steps of 90° each with periods of rest in between. As the operation of the machine is very fast, it has been found that the sudden starting and stopping of the shaft 50 and head 39 causes the teeth of gear 36 which are in engagement with pinion 49 at the stopped positions to wear. This wear in time prevents accurate positioning of the receivers 46 to receive the match packets M. P. and consequently packets are ruined and the head 39 jammed. In the old machines this required the disassembling of the parts as hereinbefore first

described. The jam of match packets against the head sometimes would stop its turning, in which event, with the old mounting of the stationary gear, breakage would occur. With my arrangement if the head is jammed the gear 36 will usually turn in the bore 34 and breakage is avoided.

When the teeth of the gear 36 at the stop positions of pinion 49 become so worn as to render the operation of the unit dangerous, by removing bolt 37 the gear 36 can be pushed out of mesh with pinion 49 and turned to bring unworn teeth to the stop positions, after which the gear 36 is again meshed with pinion 49 and bolt 37 replaced and tightened to hold gear 36 against turning under normal conditions. Thus time and material is saved. When it is desired to replace worn gears the entire unit shown in Figs. 2 and 3 can be removed from the machine by disconnecting rod 86 and removing the two bolts 31. The unit may then be taken to the bench and repaired at will, a reserve unit being substituted in the machine.

It should be mentioned that the disc 55 is so positioned that as the shaft 50 starts to turn, roller 63 will ride out of depression 56 and lift finger 65 out of the path of the packet receiver in which it was located and hold finger 65 lifted until the next receiver comes into position to receive a match packet.

In this application I make no claim to the parts numbered 1 to 9 inclusive as they constitute the subject matter of another application filed on even date herewith.

From the foregoing description taken in connection with the accompanying drawings it is thought the construction, operation and advantages of my invention will be clear to those skilled in the art.

What I claim is:

1. In a match-book making machine, a match-book receiving, reversing and delivering mechanism which includes: a main rotatable shaft; a head mounted on and rotatable with said shaft, said head including a body on which is mounted, alternately, stationary and rotatable match-book receivers spaced suitably apart, means within said body for effecting rotation of said rotatable match-book receivers, said means including a stationary gear, said means also including a gear connection, within said head, between said stationary gear and said rotatable match-book receivers; a pivoted finger projected over said head; means to effect a rise of said finger as said main rotatable head turns and to effect a fall of said finger over the match books at the position where the match books are placed on the receivers for purposes described; and means to effect turning of said main rotatable shaft.

2. In a match-book making machine, a match-book receiving, reversing and delivering mechanism which includes: a main rotatable shaft; a block having a bearing for said main rotatable shaft and having a portion provided with a bore to receive a sleeve; a head mounted on and rotatable with said shaft, said head including a body on which is mounted, alternately, stationary and rotatable match-book receivers spaced suitably apart, means within said body for effecting rotation of said rotatable match-book receivers, said means including a stationary gear having a sleeve held in the aforesaid sleeve-receiving bore, said means also including a gear connection, within said head, between said stationary gear and said rotatable match-book receivers,

disc mounted on said main rotatable shaft and having recesses in its periphery corresponding in number to and allocated to said match-book receivers; a finger having a roller to ride the periphery of said disc, the finger, when said roller is in a recess, projecting over the match-book receivers at the position where the match books are placed in the receivers; and means to effect turning of said main rotatable shaft.

3. In a match-book making machine, a match-book receiving, reversing and delivering mechanism which includes: a main rotatable shaft; a block having a bearing for said main rotatable shaft and having a portion provided with a bore to receive a sleeve; a head mounted on and rotatable with said shaft, said head including a body on which is mounted, alternately, stationary and rotatable match-book receivers spaced suitably apart, means within said body for effecting rotation of said rotatable match-book receivers, said means including a stationary gear having a sleeve held in the aforesaid sleeve-receiving bore, said means also including a gear connection, within said head, between said stationary gear and said rotatable match-book receivers, a disc mounted on said main rotatable shaft and having recesses in its periphery corresponding in number to and allocated to said match-book receivers; a finger having a roller to ride the periphery of said disc, the finger, when said roller is in a recess, projecting over the match-book receivers at the position where the match books are placed in the receivers; and means to effect turning of said main rotatable shaft.

4. In a match-book making machine wherein means are provided for folding covers, assembling covers and comb sections and wherein is provided match-book-assembling mechanism, the improvement which comprises: a match-book receiving, turning and delivering unit that includes, a main rotatable shaft; a bearing block having a mounting base and a bearing for said shaft and a split clamp portion with a bore to receive a sleeve; a head mounted on said main rotatable shaft and comprising a body on the periphery of which, at diametrically opposite places, a pair of stationary match-book receivers are mounted, said head having two diametrically opposite shaft bearings, a second rotatable shaft mounted in said opposite shaft bearings and having a pinion and carrying two rotatable match-book receivers spaced 90° from said stationary match-book receivers; a stationary gear on said main rotatable shaft within said head and meshing with said pinion and having a sleeve held in said split clamp portion; means for causing said split clamp portion to hold said stationary gear normally against turning on and moving along said main shaft, said stationary gear, when clamping force is released, being turnable about its axis and movable along said main shaft out of mesh with said pinion for purposes described; and means to turn said main shaft.

5. In a match-book making machine wherein means are provided for folding covers, assembling covers and comb sections and wherein is provided match-book-assembling mechanism, the im-

provement which comprises: a match-book receiving, turning and delivering unit that includes, a main rotatable shaft; a bearing block having a mounting base and a bearing for said shaft and a split clamp portion with a bore to receive a sleeve; a head mounted on said main rotatable shaft and comprising a body on the periphery of which, at diametrically opposite places, a pair of stationary match-book receivers are mounted, said head having two diametrically opposite shaft bearings, a second rotatable shaft mounted in said opposite shaft bearings and having a pinion and carrying two rotatable match-book receivers spaced 90° from said stationary match-book receivers; a stationary gear on said main rotatable shaft within said head and meshing with said pinion and having a sleeve held in said split clamp portion; means for causing said split clamp portion to hold said stationary gear normally against turning on and moving along said main shaft, said stationary gear, when clamping force is released, being turnable about its axis and movable along said main shaft out of mesh with said pinion for purposes described, said means for causing including a clamp bolt, and said sleeve having an annular groove to receive a portion of said bolt when the clamp is in use; and means to turn said main shaft.

6. In a match-book making machine wherein means are provided for folding covers, assembling covers and comb sections and wherein is provided match-book-assembling mechanism, the improvement which comprises: a match-book receiving, turning and delivering unit that includes, a main rotatable shaft; a bearing block having a mounting base and a bearing for said shaft and a split clamp portion with a bore to receive a sleeve; a head mounted on said main rotatable shaft and comprising a body on the periphery of which, at diametrically opposite places, a pair of stationary match-book receivers are mounted, said head having two diametrically opposite shaft bearings, a second rotatable shaft mounted in said opposite shaft bearings and having a pinion and carrying two rotatable match-book receivers spaced 90° from said stationary match-book receivers; a stationary gear on said main rotatable shaft within said head and meshing with said pinion and having a sleeve held in said split clamp portion; means for causing said split clamp portion to hold said stationary gear normally against turning on and moving along said main shaft, said stationary gear, when clamping force is released, being turnable about its axis and movable along said main shaft out of mesh with said pinion for purposes described; and means to turn said main shaft; said bearing block having an ear; a finger-carrying block pivoted to said ear and having a finger extending over said head into proximity to said match-book receivers when they are in their receiving positions; and means on said main shaft and cooperatively engaging said finger-carrying block to lift said finger as said head turns, to clear said match-book receivers.

said ear and having a finger extending over said head into proximity to said match-book receivers when they are in their receiving positions; and means on said main shaft and cooperatively engaging said finger-carrying block to lift said finger as said head turns, to clear said match-book receivers.

7. In a match-book making machine wherein means are provided for folding covers, assembling covers and comb sections and wherein is provided match-book-assembling mechanism, the improvement which comprises: a match-book receiving, turning and delivering unit that includes, a main rotatable shaft; a bearing block having a mounting base and a bearing for said shaft and a split clamp portion with a bore to receive a sleeve; a head mounted on said main rotatable shaft and comprising a body on the periphery of which, at diametrically opposite places, a pair of stationary match-book receivers are mounted, said head having two diametrically opposite shaft bearings, a second rotatable shaft mounted in said opposite shaft bearings and having a pinion and carrying two rotatable match-book receivers spaced 90° from said stationary match-book receivers; a stationary gear on said main rotatable shaft within said head and meshing with said pinion and having a sleeve held in said split clamp portion; means for causing said split clamp portion to hold said stationary gear normally against turning on and moving along said main shaft, said stationary gear, when clamping force is released, being turnable about its axis and movable along said main shaft out of mesh with said pinion for purposes described, said means for causing including a clamp bolt, and said sleeve having an annular groove to receive a portion of said bolt when the clamp is in use; and means to turn said main shaft; said bearing block having an ear; a finger-carrying block pivoted to said ear and having a finger extending over said head into proximity to said match-book receivers when they are in their receiving positions; and means on said main shaft and cooperatively engaging said finger-carrying block to lift said finger as said head turns, to clear said match-book receivers.

NELSON E. GARRISON.
